US0D1000464S

(12) **United States Design Patent** (10) **Patent No.:** **US D1,000,464 S**
Stusynski et al. (45) **Date of Patent:** **** Oct. 3, 2023**

(54) **DISPLAY SCREEN OR PORTION THEREOF WITH GRAPHICAL USER INTERFACE**

(71) Applicant: **Sleep Number Corporation**, Minneapolis, MN (US)

(72) Inventors: **Stacy Stusynski**, Minneapolis, MN (US); **Russell Hampton**, San Francisco, CA (US); **Kelsey Kong**, San Francisco, CA (US); **Kristen Elizabeth Swenby**, Blaine, MN (US); **Julie Elepano**, Minneapolis, MN (US); **Carol Lynn Herman**, Minneapolis, MN (US)

(73) Assignee: **Sleep Number Corporation**, Minneapolis, MN (US)

(**) Term: **15 Years**

(21) Appl. No.: **29/837,293**

(22) Filed: **May 4, 2022**
